UNITED STATES PATENT OFFICE.

SAMUEL SEGAL, OF NEW YORK, N. Y.

KEY BLANK.

Application filed November 24, 1925. Serial No. 71,063.

This invention relates to an improved type of key blank.

It is an object to provide an article of this character which may be produced at less expense than similar articles as heretofore manufactured and which may be cut more expeditiously to provide a cheaper finished key.

Another object of the invention is that of providing a blank in which the percentage of faulty cuts will be reduced to a minimum.

A still further object is that of furnishing a blank which may be utilized to advantage in testing the accuracy of a key-cutting machine so that the correctness of the gauge thereof may be readily proved.

An additional object is that of providing an article which will efficiently perform the purposes for which it is intended.

Other objects of the invention will in part be obvious and will in part appear hereinafter.

With these and further objects in mind the invention comprises an article of manufacture possessing the features, properties and the relation of elements which will be exemplified in the article hereinafter described and the scope of the application of which will be indicated in the claims.

For a fuller understanding of the nature and objects of the invention reference should be had to the following detailed description taken in connection with the accompanying drawings, in which:

Figure 1 is a side elevation of a key blank embodying the improved construction of the present invention and shows the same applied to a cylinder lock, the latter being indicated in dotted lines;

Fig. 2 is a transverse sectional view of said blank; and

Fig. 3 is a view similar to Fig. 1 but showing a different form of the invention from that shown in the preceding figures.

This invention is particularly directed to blanks for keys to be used in cylinder locks. In locks of this character the housing is formed with a bore within which a plug is rotatable. This plug is formed with a longitudinally-extending key slot into which one or more ribs usually extend. A number of openings have their inner ends in communication with this key slot and extend through to the outer face of the plug, and pins are positioned within these openings. The housing is ordinarily formed with openings corresponding in number to the plug openings.

Pins are positioned one within each of the housing openings and are usually urged into the bore thereof by springs. Normally, the openings of these two elements align, and the tumbler pins of the housing extend into the openings of the plug and thus prevent a turning thereof.

Any suitable number of openings and pins are employed, and they are usually spaced equidistant from each other. Ordinarily, the plug pins vary in length in order to provide what may be termed the permutation of the lock, and the key which operates the lock is cut to have bittings which vary in length inversely to the pin lengths of the plug. Thus, when the key is disposed within the key slot of the cylinder plug the outer ends of the pins will all lie flush with the outer plug face and move the housing pins into retracted position so that the plug may be turned within the housing to operate the lock.

Key blanks are of course furnished in varying lengths corresponding to the length of the key cylinder and in order to permit of the forming of bittings corresponding in number to the number of tumbler pins which are to be operated. Different types of blanks are furthermore furnished which have an inherently different arrangement of grooves extending longitudinally of their bodies and corresponding to the arrangement of longitudinally-extending ribs forming a part of the key slot of the plug. It has been usual in referring to the cutting of the longest practicable biting—i. e., the projection of the key which has its apex at a maximum distance from the key axis—as necessitating a zero cut of the blank, and progressively shorter bittings have been referred to by corresponding numbers or symbols.

With the foregoing in mind, the present invention provides a key blank preferably of the cylinder lock type in which that edge of the blank in which the bittings are to be cut may be provided with a series of notches at points in line with the points at which the tumbler pins will engage the key when the plug is turned. Thus, in the drawings, the numeral 5 indicates the body of the blank key, and 6 the grooves, which extend longitudinally thereof; the reference number 7 indicating that edge of the key in which the bittings are to be formed, and 8 the notches in this edge. These notches, in the present instance, extend to a depth equal to a zero-cut biting but it will be appreciated that, if

desirable, they might extend to a less depth.

However, according to the illustrated form of the invention, by having the notches of just a zero-cut depth, no cutting on the part 5 of the key-cutting machine will be necessary to form the apex of a zero-cut bitting when the same is encountered. In other words, that part of the cutting of the key blank has been accomplished at the time the blank was died 10 out.

Accordingly, when an operator has a key blank which is to be cut to provide a finished key, it will be obvious that less cutting has to be done in order to provide such key than 15 has heretofore been necessary where a conventional blank was being utilized. It is furthermore apparent that due to a blank being furnished which has a roughened upper edge (i. e., notches in such edge) the thumb 20 or fingers of an operator will engage the key so that the blank will be rammed home in the cutting machine, and consequently, the bittings in the key being formed will correspond in location, with respect to the key 25 body, to the bittings of the "guide" key. In dieing out blanks of the type embraced in the present invention more scrap metal will be available incident to the forming of the notches, so that aside from the fact that the 30 dieing-out operation will be no more expensive than in the case of the conventional key blank, the blank of the present invention may be manufactured more cheaply, and it will also be obvious that if an operator is desirous 35 of checking the gauge of the cutting machine this may be readily accomplished by simply utilizing two of these blanks and placing one of them in the guide-holder, and the other in the blank-holder. Under these conditions, 40 and with the cutting machine not operating, the cutter of the latter should ride into the notches of the blank at exactly those moments when the guide of the machine enters the notches of a corresponding blank held by the 45 guide clamp. In addition to this advantage, an operator when utilizing a blank constructed within the terms of the present invention will always present the bitting edge to the cutting or milling tool, in that this edge will 50 be plainly indicated.

It will be appreciated that in lieu of the gauge marks provided by the notches other gauge marks might be furnished, as for example, at 9 in Fig. 3. Thus the gauge of the 55 machine may be accurately checked by key blanks of this character. Also, the notches may be of greater area than those shown in Figs. 1 and 2, and in fact, if desired—as has also been shown in Fig. 3—the entire bitting 60 edge of the blank may be reduced to a zero cut, so that an even greater amount of scrap metal will be available when producing a key blank of this type.

From the foregoing it will be appreciated 65 that the objects of the invention have been

accomplished, and since certain changes may be made in the above article, and different embodiments of the invention could be made, without departing from the scope thereof it is intended that all matter contained in the 70 above description or shown in the accompanying drawings shall be interpreted as illustrative and not in a limiting sense.

It is also to be understood that the following claims are intended to cover all of the 75 generic and specific features of the invention herein described and all statements of the scope of the invention which as a matter of language might be said to fall therebetween.

Having described my invention, what I 80 claim as new and desire to secure by Letters Patent is:

1. As an article of manufacture, a key blank, including a body having an edge in which bittings are to be formed by a key-cutting machine and a series of notches in 85 said edge.

2. As an article of manufacture, a key blank, including a body having an edge in which bittings are to be formed by a key-cutting machine and a series of notches in 90 said edge and of a depth not in excess of a zero cut.

3. As an article of manufacture, a key blank, including a body having an edge in which bittings are to be formed by a key-cutting machine and a series of notches in 95 said edge and at points in line with the tumbler pins of a lock which said key is to operate.

4. As an article of manufacture, a key blank, including a body having an edge in which bittings are to be formed by a key-cutting machine and a series of notches in 100 said edge and at equi-spaced points in said edge and in line with the tumbler pins of a lock which said key is to operate, the depth of said notches being not in excess of a zero cut.

5. As an article of manufacture, a key blank, in one edge of which bittings of different heights are to be formed by a key-cutting machine, such edge of the blank being 110 partially cut prior to its application to the cutting machine.

6. As an article of manufacture, a key blank, including a body having an edge in which the finished bittings are to be formed by a key-cutting machine, said edge presenting partly formed bittings.

7. As an article of manufacture, a key blank having a groove in one of its side faces extending longitudinally of its body and presenting an edge in which bittings are to be formed by a key-cutting machine and a series 125 of notches in said edge.

8. As an article of manufacture, a key blank having a groove in one of its side faces extending longitudinally of its body and presenting an edge in which bittings are to be 130

- formed by a key-cutting machine and a series of notches in said edge and of a depth not in excess of a zero cut.
9. As an article of manufacture, a key blank to be rotated and including a body having an edge in which a permutation of bittings of various heights are to be cut by a key-cutting machine, and a series of gauge marks associated with such edge.
10. As an article of manufacture, a key blank for use in the rotatable plug of a cylinder lock and including a body having an edge in which a permutation of bittings of various heights are to be cut by a key-cutting machine, and a series of gauge marks for such machine and associated with such edge and at equi-spaced points in said edge in line with the tumbler pins of a lock which said key is to operate.
11. As an article of manufacture, a key blank to be rotated to operate a lock and including a body having an edge in which a permutation of bittings of various heights are to be cut by a key-cutting machine, such edge being substantially continuous and of a height substantially equal to the highest bitting which is to be cut in said edge.
12. As an article of manufacture, a key-blank for use in connection with the rotatable plug of a cylinder lock and including a body having an edge in which bittings are to be formed by a key-cutting machine, portions of such edge being of a height substantially equal to the highest bitting which is to be cut in such edge.

In testimony whereof I affix my signature.

SAMUEL SEGAL
